(57) CLAIM

The ornamental design for a dog-adorned basketball sport pet, as shown and described.

DESCRIPTION

FIG. 1 is a front and side perspective view of a dog-adorned basketball sport pet showing my new design;

FIG. 2 is a front elevation view thereof;

FIG. 3 is a rear elevation view thereof;

FIG. 4 is a left side elevation view thereof, the left side elevation view being a mirror image thereof;

FIG. 5 is a top plan view thereof;

FIG. 6 is a bottom plan view thereof; and,

FIG. 7 is a front and side perspective view of a dog-adorned basketball sport pet showing my new design according to a second embodiment thereof in which full lines are used to illustrate a contrasting-color surface treatment applied to such portions of the dog-adorned basketball sport pet.

The broken lines of FIGS. 1-7 are for illustrative purposes only and form no part of the claimed design.
